UNITED STATES PATENT OFFICE

154,424

DESIGN FOR A SAFETY REEL FOR CHILDREN OR SIMILAR ARTICLE

Edward Oswald and Johann G. Wolf,
Bloomfield, N. J.

Application April 30, 1948, Serial No. 146,073

Term of patent 7 years

(Cl. D41—1)

To all whom it may concern:

Be it known that we, Edward Oswald and Johann George Wolf, both citizens of the United States, residing at 19 Baldwin Street, Bloomfield, New Jersey, and 714 Broad Street, Bloomfield, New Jersey, respectively, pray that Letters Patent may be granted to them for the term of 7 years for the new, original, and ornamental Design for Safety Reel for Children or Similar Article, set forth in the following specification, reference being had to the accompanying drawing, forming a part thereof, wherein:

Fig. 1 is a side perspective view of a safety reel for children embodying our design,

Fig. 2 is a top perspective view thereof,

Fig. 3 is a rear elevational view thereof, taken on a slightly reduced scale.

We claim:

The ornamental design for a safety reel for children or similar article, as shown.

EDWARD OSWALD.
JOHANN G. WOLF.
